UNITED STATES PATENT OFFICE.

ABRAM TOLKOWSKY, MAURICE TOLKOWSKY, AND ISIDORE TOLKOWSKY,
OF ANTWERP, BELGIUM.

DESIGN FOR A CUT STONE.

SPECIFICATION forming part of Design No. 36,600, dated October 27, 1903.

Application filed July 29, 1903. Serial No. 167,500. Term of patent 14 years.

To all whom it may concern:

Be it known that we, ABRAM TOLKOWSKY, MAURICE TOLKOWSKY, and ISIDORE TOLKOWSKY, subjects of the Czar of Russia, residing in Antwerp, in the Kingdom of Belgium, have invented a certain new, original, and ornamental Design for Cut Stones; and we do hereby declare the following to be a full, clear, and exact specification of the invention, such as will enable others skilled in the art to which it appertains to make and use the same, reference being had to the accompanying drawings, which form a part of this specification.

The figures of the drawings show the cut

stone in top plan view, Figure 1, and in underneath view, Fig. 2.

What we claim as new, and desire to secure by Letters Patent, is—

The ornamental design for a cut stone substantially as herein shown.

In testimony that we claim the foregoing we have hereunto set our hands this 16th day of July, 1903.
